[57] CLAIM

The ornamental design for a combined coaster and ash tray holder, as shown and described.

DESCRIPTION

FIG. 1 is a top front perspective view of a combined coaster and ash tray holder showing our new design; FIG. 2 is a top plan view thereof;

FIG. 3 is a rear elevational view thereof;

FIG. 4 is an end elevational view thereof;

FIG. 5 is a bottom plan view thereof on a reduced scale; and

FIG. 6 is a modification of our design of FIGS. 1—5 wherein a cut-out or slotted opening has been provided in the upper plate.
